UNITED STATES PATENT OFFICE.

WILLIAM EDGAR BRAYMER, OF KIEFER, OKLAHOMA.

SWING.

1,406,529.

Specification of Letters Patent. Patented Feb. 14, 1922.

Application filed March 10, 1921. Serial No. 451,096.

To all whom it may concern:

Be it known that I, WILLIAM E. BRAYMER, a citizen of the United States, and a resident of Kiefer, in the county of Creek and State 5 of Oklahoma, have invented certain new and useful Improvements in Swings, of which the following is a specification.

This invention relates to a swing, and more particularly to a foot rest therefor.

10 The object of the invention is to provide a foot rest for swings of the so-called "porch" type, which will add greatly to the comfort of the occupant.

15 It is also an object of the invention to provide a foot rest which may be readily attached to a standard type of porch swing.

A further object of the invention is to employ spring means in connection with the foot rest which will permit the same to 20 lower when the user places his foot thereon preparatory to entering the swing, and thus making it easier for the user to become seated.

The invention is illustrated by way of 25 example in the accompanying drawings, in which—

Figure 1 is a front elevation and showing the application of my invention,

Figure 2 is a side elevation,

30 Figure 3 is a longitudinal transverse section showing the construction of spring hangers or bars,

Figure 4 is a transverse section of Figure 3,

35 Figure 5 is a fragmentary side elevation of the adjustable connection of the spring bars or hangers,

Figures 6 and 7 are detail views of links 40 used in connection with the spring bars or hangers.

Referring to the drawings more particularly, 10 designates generally the swing frame and seat which is suspended in the usual manner by the means of the chains or 45 cables as indicated at 11. The frame has at each end a cross member 12 and to the rear end of each cross member there is pivotally connected one end of a hanger bar 13, said bar being slightly curved as at 14 for 50 a purpose which will later appear. The lower end of each bar 13 is pivotally connected to one end of the foot board 15 by means of an L-shaped bolt 16, as shown. The lower ends of the bars 13 are connected 55 near the rear end portion of the foot board 15, the purpose of which will later become

apparent. Front and rear links 17 are pivoted to the forward and rear portions of the swing as indicated at 18. The lower end of each link 17 has formed thereon a cross member or head 19 which is adapted to hold on each link a screw cap 20. Each screw cap is threaded on one end of a tubular member 21 within which is housed a coil spring 22. Through the lower end of each 60 tubular member 21 there passes a rectangular shaped bar 23, the upper end of which is formed with a head 24 engaged by the coil spring 22. The lower end of each bar 23 is slotted as at 25.

To each rear member 23 there is connected a bar 26, the lower end of which is pivotally connected by means of an L-shaped bolt 27 to the forward portion of the foot board 15. The upper end of each bar 26 75 is slotted as at 28, and adjustably held or connected with the lower end of its respective bar 23 by the means of a bolt and wing nut as indicated at 29.

The lower ends of the forward bars 23 80 are pivotally connected to the upper ends of the bars 26 by means of the link bars 30, the connecting end of the links 30 and bars 23 being slotted and adjustably connected or held together by means of a bolt 85 and wing nut 31; also between the lower end of the link bars 30 and the intermediate portion of the hanger bars 13 there is pivotally attached at each of its ends a link member 32. The link members 32 and the 90 bar links 30 are curved as shown in Figures 6 and 7 for the obvious purpose of permitting free movement of the associated bars and links.

In the operation of the present device, 95 the foot board 15 is normally held in the position shown in Figure 2. When the person prepares to enter the swing he will naturally place one foot upon the foot board which will be permitted to swing downward 100 and thus lower the same and make it easy for the person to be seated in the swing. The lowering movement of the foot board is of course, permitted by the downward movement of the forward bars 23, said bars 105 being permitted to be moved downward by the depression of the forward spring coils 22. At the same time, the forward portion of the foot board 15 will be permitted to be moved downwardly, that is, the foot 110 board will become inclined from the horizontal. This movement is permitted by the

downward movement of the rear bars 25. The purpose of this is that the slanting position of the foot board is the natural position the foot of the user of the swing 5 would assume when stepping into or attempting to enter the swing. Immediately upon the user being seated in the swing, his foot of course, will be raised by the action of the forward springs 22 and likewise his 10 feet will be brought to a horizontal position by the action of the rear springs 22. When the user leaves the swing, the movement of the foot board 15 will be substantially the same as that described when the 15 user was entering the swing.

I claim:

1. A foot rest for swings, comprising in combination, a swing frame, a pair of hanger bars having their one end pivotally connected to the rear end portion of the swing frame, and their other end connected to a foot board extending therebetween, and distendible spring means between the intermediate portion of each hanger bar and the 25 forward end of the swing frame.

2. A foot rest for swings, comprising in combination, a swing frame, a pair of hanger bars having their one end pivotally connected to the rear end portion of the swing 30 frame, and their other end pivotally connected to a foot board extending therebetween, and distendible spring means between the intermediate portion of each hanger bar and the forward end of the swing 35 frame.

3. A foot rest for swings, comprising in combination, a swing frame, a pair of hanger bars having their one end pivotally connected to the rear end of the swing frame, 40 and the other end pivotally connected to a foot board extending therebetween, said last named end being connected to the foot board near the rear portion thereof, a distendible spring means connected between 45 each forward end of the swing frame and the intermediate portion of each hanger bar, and distendible spring means connected between each front end of said foot board and the associated end of the swing frame.

4. A swing foot rest comprising in combination, a swing frame, a hanger bar pivotally attached to each rear end of the frame, a foot board having its ends pivotally connected to the lower ends of said hanger bars, 55 a bar pivotally connected to each forward end of the spring frame, said bars being divided and having a coil spring associated therewith to normally hold their divided ends together, and pivotal connecting means 60 between the lower end of each of the divided bars and the associated first named hanger bar.

5. A swing foot rest comprising in combination, a swing frame, a hanger bar pivotally attached to each rear end of the frame,

a foot board having its ends pivotally connected to the lower ends of said hanger bars, a bar pivotally connected to each forward end of the spring frame, said bars being divided and having a coil spring associated therewith to normally hold their divided ends together, and pivotal connecting means between the lower end of each of the divided bars and the associated first named hanger bar, and means by which the length of said 70 divided bars may be adjusted. 75

6. A swing foot rest comprising in combination, a swing frame, a hanger bar pivotally attached to each rear end of the frame, a foot board having its ends pivotally connected to the lower ends of said hanger bars, said foot board being disposed in a horizontal plane and the ends of the hanger bars connected near the rear portion thereof, a bar pivotally connected to each forward 80 end of the spring frame, said bar being divided and having a coil spring associated therewith to normally hold their divided ends together, and a second pair of divided bars with coil springs to normally hold their 85 divided ends together, pivotally attached at their upper ends to the rear ends of the swing frame and at their lower ends to the forward ends of the foot board.

7. A swing foot rest comprising in combination, a swing frame, a hanger bar pivotally attached to each rear end of the frame, a foot board having its ends pivotally connected to the lower ends of said hanger bars, 90 said foot board being disposed in a horizontal plane and the ends of the hanger bars connected near the rear portion thereof, a bar pivotally connected to each forward end of the spring frame, said bar being divided and having a coil spring associated therewith to normally hold their divided ends together, and a second pair of divided bars with coil springs to normally hold their 95 divided ends together, pivotally attached at their upper ends to the rear ends of the swing frame and at their lower ends to the forward ends of the foot board, and pivotal connecting means between the lower ends of the first named divided bars and the intermediate portion of the last named 100 divided bars.

8. The combination with a seat, of yieldable supporting devices suspended therefrom, a bar having connection with said yieldable supporting devices, a foot board having 105 pivotal connection with said bar, and a rigid hanger suspended from said seat and having pivotal connection with the foot board.

9. The combination with a seat, of yieldable supporting devices suspended therefrom, a bar having connection with said yieldable supporting devices, a foot board having pivotal connection with said bar, a rigid hanger suspended from said seat and having pivotal connection with the foot 110 115 120 125 130

- board, and a link connecting the intermediate portion of said hanger with said bar.
10. A foot rest for seats comprising a pair of diverging supporting members inclusive of yieldably connected upper and lower sections, a bar connected to said lower sections, a foot board supported by said bar, and a hanger pivoted to said foot board and having means whereby the same may be attached to a seat.
11. A foot rest for seats comprising a pair of diverging supporting members inclusive of yieldably connected upper and lower sections, a bar connected to said lower sections, a foot board supported by said bar, a hanger pivoted to said foot board and having means whereby the same may be attached to a seat, and a link pivoted to said hanger and said bar.

WILLIAM EDGAR BRAYMER.
